UNITED STATES PATENT OFFICE.

JOHN EDWARD GUENTHER, OF OWENSBOROUGH, KENTUCKY.

WATER-COOLING ATTACHMENT FOR REFRIGERATORS.

SPECIFICATION forming part of Letters Patent No. 314,175, dated March 17, 1885.

Application filed June 28, 1884. (No model.)

To all whom it may concern:

Be it known that I, JOHN EDWARD GUENTHER, a citizen of the United States, and a resident of Owensborough, in the county of Daviess and State of Kentucky, have invented 5 certain new and useful Improvements in Water-Cooling Attachments for Refrigerators; and I do hereby declare that the following is a full, clear, and exact description of the invention, which 10 will enable others skilled in the art to which it appertains to make and use the same, reference being had to the accompanying drawings, which form a part of this specification, and in which—

15 Figure 1 is a perspective view of my improved water-cooling attachment for refrigerators. Fig. 2 is a transverse vertical sectional view of a refrigerator provided with my attachment; and Fig. 3 is a vertical section on 20 line α α , Fig. 2.

Similar letters of reference indicate corresponding parts in all the figures.

My invention has relation to that class of 25 water-cooling devices for refrigerators in which the water is drawn from a closed vessel upon which the ice rests, and which is supplied with water as it is drawn off from a reservoir located above it; and it consists in the improved construction and combination of parts 30 of such a device, which is removable, and may be inserted into a refrigerator of any construction, as hereinafter more fully described and claimed.

In the accompanying drawings, the letter 35 A indicates the refrigerator, which may be of any desired construction, and B is the ice-chamber, which communicates with the provision-chamber D through passages C C, through which the cold air may pass into the 40 said chamber.

A drip-tube, E, extends downward from the bottom of the ice-chamber, carrying off the water from the ice as it melts.

The attachment, which is shown at F, consists of the reservoir G, of suitable dimensions, and either open at the top or provided with a suitable cover, and of the flat closed tank or chamber I. This tank is secured below and to one side of the reservoir by means 45 of a bracket, H, at one end, and an elbow or bent pipe, L, at the other end, one of its up-

per side edges facing the lower side edge of the reservoir.

One end of the tank has a screw-threaded opening, J, into which the threaded shank of 55 a faucet, K, fits, which faucet may be inserted through the side of the refrigerator-casing.

The tank is provided with a vent-pipe, M, extending upward to the height of the highest water-level in the reservoir, serving to allow 60 the air contained in the tank to escape when the tank and reservoir are filled, inasmuch as the air contained in the flat tank would offer considerable resistance to the water, the only escape for the air being through the narrow 65 elbow or bent pipe through which the water has to pass.

It will be seen that the ice resting upon the top of the flat tank will effectually cool the water contained in the said tank, and that as 70 the water is drawn off from the tank through the faucet the water from the reservoir will descend into the tank and be cooled, and the drinking-water will at no time be in contact with the ice, or be exposed to the odors or 75 vapors arising from the contents of the refrigerator.

It will furthermore be seen that the attachment may be inserted into a refrigerator of 80 any construction, all the work necessary being the boring of a perforation through the side of the refrigerator-casing for the passage of the shank of the faucet.

I am aware that it is not new to have water-cooling devices in refrigerators consisting of 85 a tank which is directly exposed to contact with the ice, and a reservoir communicating with the tank, and I do not wish to claim such construction, broadly; but

I claim—

1. A water-cooling attachment for refrigerators, consisting of a reservoir, a flat closed box or tank attached below and to one side of the reservoir, communicating with the same by means of an elbow or bent pipe having an 95 upright vent-pipe and provided with a threaded outlet-aperture, and a faucet having a threaded shank fitting in the said aperture and adapted to be inserted through the side of the refrigerator-casing, as and for the purpose 100 shown and set forth.

2. The combination, with a refrigerator of

the usual construction, of a water-cooling attachment consisting of a reservoir and a flat box or tank communicating with the reservoir by means of a bent pipe and secured below and 5 to one side of the said reservoir, provided with an upright vent-pipe and with a removable faucet adapted to be inserted through the side of the refrigerator-casing into the end of the tank, as and for the purpose shown and set 10 forth.

In testimony that I claim the foregoing as my own I have hereunto affixed my signature in presence of two witnesses.

JOHN EDWARD GUENTHER.
